UNITED STATES PATENT OFFICE.

GEORGE M. GRAHAM, OF CHICAGO, ILLINOIS, ASSIGNOR, BY MESNE ASSIGNMENTS, TO
SUSPENSION STEEL CONCRETE COMPANY, A CORPORATION OF DELAWARE.

REINFORCED CONCRETE STRUCTURE.

974,656.

Specification of Letters Patent.

Patented Nov. 1, 1910.

Application filed April 21, 1909. Serial No. 491,345.

To all whom it may concern:

Be it known that I, GEORGE M. GRAHAM, a citizen of the United States of America, and a resident of Chicago, in the county of 5 Cook and State of Illinois, have invented certain new and useful Improvements in Reinforced Concrete Structures, of which the following is a specification.

This invention relates to reinforced concrete structures in which wires or rods in spaced relation are secured to a round border frame to form a skeleton center for receiving and supporting the concrete mass during the erection of the structure. And 10 the present improvement has for its object to provide a simple and efficient formation and combination of the marginal frame and skeleton wire or rod centers forming a unit of the structure, in which the proper tension of the component wires or rods of said center is attained in a ready, certain and convenient manner, and with which a more substantial and rigid outer web is provided for the coating of concrete forming the 15 outer portion of a vertical wall, than is necessary for the inner portion of said wall, and a like increased strength and rigidity in the upper or tread surface of a floor of the structure over what is provided for the portion thereof which forms a ceiling, all as will hereinafter more fully appear.

In the accompanying drawings:—Figure 1, is a detail sectional plan of the present construction as adapted for a floor or other 20 horizontal part of a concrete structure. Fig. 2, is a sectional elevation, on line α — α , Fig. 1, showing the wire or rod center in course of application. Fig. 3, is a similar view of the same in a finished condition. 25 Fig. 4, is a detail front elevation of the construction as applied to an upright portion of the reinforcing frame aforesaid.

Similar numerals of reference indicate like parts in the different views.

Referring to the drawings, 1 represents a series of vertical posts or columns, and 2 a series of horizontal round beams or girders coupled together and to the posts 1 by coupling members 3 to form the skeleton border 30 frame which supports the wire or rod center hereinafter described, and the inclosing mass of concrete to form the walls, floors, etc., of a reinforced concrete structure. And said reinforcing frame is preferably of the suspension type described in detail in a com-

panion application for Letters Patent Serial No. 491,344, filed April 21, 1909.

The material feature of the present improvement consists in the formation of the wire or rod center above referred to, in a manner that will afford a maximum amount of strength and rigidity to the center with a minimum amount of material, and a ready and convenient application and an effective tensioning of the same to the required degree. To such ends said formation of the wire or rod center will comprise the following:—

4 are a series of independent links of the hoop type and which extend between and around a pair of opposed beams 2, and preferably in the crossed relation shown, to constitute the skeleton web or center of the reinforcing frame aforesaid. In the present improvement each of said links is formed from 70 a wire or rod of the requisite length placed under the opposed pair of round beams 2 to constitute a single wire under strand 5 of the skeleton center or web; then looped around the respective beams and extended 75 in opposite directions to constitute a double wire upper strand 6 of said skeleton center or web. The respective ends of the wire or rod are then successively looped around the respective beams, and their terminals formed 80 into attaching coil splices 7 encircling the upper double wire strands 6 aforesaid. In practice a flattened loop shaped link 4, aforesaid is formed around the beams in the above described construction, with the exception of the last attaching coil splice 7, under ordinary hand tension, after which predetermined power tension is applied to the free upper strand to bring the lower strand and the 85 companion upper strand under the required 90 tension, after which the last attaching coil splice 7 is formed to maintain the various strands at the required tension. In the application of such final or power tension, the first attaching coil splice 7 permits of a 95 ready independent movement of one upper strand past the other, as the various strands are drawn to the required tension.

After the completion of the series of links 4 as above described, and at any time previous to the application of the concrete mass thereto, any particular link will have its tension increased when so required by forming a twist 8 in the double wire upper strand 6, as illustrated in Fig. 4.

2

As applied to a floor or other horizontal portion of a structure, the double wire strands above described will be uppermost and will receive the greater stress of the 5 green concrete mass used in forming the floor proper, while the single wire strands will be undermost and will receive the lesser stress of the green concrete mass used in forming the ceiling, and which has a much 10 less thickness than is necessary in the floor proper.

The operation of applying the concrete mass may be any usual method, it is however preferred to use the particular method 15 described in detail in my prior Letters Patent No. 888,999, dated May 26, 1908.

As applied to a wall or other vertical portion of a structure, the double wire strands aforesaid will be preferably arranged to the 20 outside, so that the concrete mass forming the outer layer or thickness of the wall will receive the greater amount of support and corresponding strength.

Having thus fully described my said invention what I claim as new and desire to 25 secure by Letters Patent, is:—

1. A reinforcing frame for concrete structures comprising, a series of round border beams, and a skeleton center of flattened 30 hoop shaped links extending from beam to beam, and each consisting of a single strand at one side and a double strand at the other side and formed from a single rod or wire the terminals of which end in coil splices surrounding the aforesaid double strands; 35 substantially as set forth.

2. A reinforcing frame for concrete structures comprising, a series of round border

beams, and a skeleton center of flattened 40 hoop shaped links arranged in crossed relation and extending from beam to beam, and each consisting of a single strand at one side and a double strand at the other side and formed from a single rod or wire the terminals of which end in coil splices surrounding 45 the aforesaid double strands, substantially as set forth.

3. A reinforcing frame for concrete structures comprising, a series of round border beams, and a skeleton center of flattened 50 hoop shaped links extending from beam to beam, and each consisting of a single strand at one side and a double strand at the other side and formed from a single rod or wire 55 the terminals of which end in coil splices surrounding the aforesaid double strands, said strands having a tensioning twist, substantially as set forth.

4. A reinforcing frame for concrete structures comprising, a series of round border beams, and a skeleton center of flattened 60 hoop shaped links arranged in crossed relation and extending from beam to beam, and each consisting of a single strand at one side and a double strand at the other side and formed from a single rod or wire the terminals of which end in coil splices surrounding 65 the aforesaid double strands, said strands having a tensioning twist, substantially as set forth.

Signed at Chicago, Illinois, this 12th day 70
of April 1909.

GEORGE M. GRAHAM.
